[57] CLAIM

The ornamental design for a turning tool holder, as
shown and described.

DESCRIPTION

FIG. 1 is a bottom-right perspective view of a turning
tool holder showing my new design, the broken-line
showing of a turning blade being environmental only
and forming no part of the claimed design;

FIG. 2 is a front elevational view;

FIG. 3 is a right side elevational view;

FIG. 4 is a left side elevational view;

FIG. 5 is a top plan view;

FIG. 6 is a front elevational view of a second embodiment
of my new design of FIGS. 1-5, all other sides
being identical thereto;

FIG. 7 is a right side elevational a third embodiment of
FIGS. 1-5 of my new design;

FIG. 8 is a front elevational view; and other side being
identical thereof.

FIG. 1

FIG. 2

FIG. 3

FIG. 4

FIG. 5

FIG. 6

FIG. 7

FIG. 8
